[57] CLAIM

The ornamental design for a point-of-sale system terminal console, substantially as shown and described.

DESCRIPTION

FIG. 1 is a front elevational view of a point-of-sale system terminal console showing our new design;

FIG. 2 is a top plan view thereof;

FIG. 3 is a rear elevational view thereof;

FIG. 4 is a bottom plan view thereof;

FIG. 5 is a left side elevational view thereof;

FIG. 6 is a right side elevational view thereof.

*Fig. 1**Fig. 2**Fig. 3**Fig. 4**Fig. 5**Fig. 6*
